REFRIGERATING APPARATUS

Martin J. Goulooze, Grand Rapids, Mich., assignor to Nash-Kelvinator Corporation, Detroit, Mich., a corporation of Maryland

Application July 18, 1941, Serial No. 402,900

2 Claims. (CL 220—15)

The present invention relates to refrigerating apparatus, and more particularly to refrigerator cabinet construction.

It is an object of the present invention to provide an improved arrangement for mounting a food compartment liner in a refrigerator cabinet.

Another object of my invention is to provide straps for securing an inner liner to the outer casing of a refrigerator cabinet and to secure the straps to the inner liner by the same devices which support the shelves within said liner.

Another object of the present invention is to provide relatively thin gauge metallic breaker strips of low heat conductivity for interconnecting the inner and outer walls of a refrigerator cabinet, and to arrange for securing said breaker strip to said walls in an improved manner.

It is a further object of the present invention to provide for the assembly of the cabinet whereby its internal and external wall surfaces are free of projecting or visible affixing means, such as screw heads or the like.

The invention itself, however, both as to its organization and its method of operation, together with additional objects and advantages thereof, will best be understood from the following description of specific embodiments when read in conjunction with the accompanying drawings.

In the drawings:

Fig. 1 is a front view of a refrigerator cabinet with parts broken away;

Fig. 2 is a cross sectional view taken along line 2—2 of Fig. 1 with parts shown in elevation;

Fig. 3 is a cross sectional view taken along line 3—3 of Fig. 2;

Fig. 4 is a fragmentary enlarged cross sectional view taken along line 4—4 of Fig. 1;

Fig. 5 is a fragmentary enlarged cross sectional view taken along line 5—5 of Fig. 3;

Fig. 6 is a fragmentary cross sectional view taken along the line 6—6 of Fig. 1;

Fig. 7 is a fragmentary cross sectional view taken along line 7—7 of Fig. 6;

Fig. 8 is a rear perspective view of a corner trim;

Fig. 9 is a fragmentary cross sectional view similar to Fig. 4 showing a modified form of the invention;

Fig. 10 is a cross sectional view of another modified form of the invention;

Fig. 11 is a cross sectional view of still another modified form of the invention;

Fig. 12 is a fragmentary cross sectional view

similar to Fig. 2 illustrating a further modified form of the invention;

Fig. 13 is a fragmentary cross sectional view taken along line 13—13 of Fig. 12; and

Fig. 14 is a fragmentary cross sectional view taken along line 14—14 of Fig. 12.

Shown in the drawings is a refrigerator cabinet 20 having a food storage compartment 22 and a machine compartment 24. Across opening 25 to the food storage compartment is closed by a pivotally mounted door 26. The compartment 22 is formed by a liner or inner shell 27 having side, top, bottom and rear walls. The edges of the side, top and bottom walls around the opening 25 are marginally flanged outwardly at right angles to form a portion of the front wall of the cabinet, as at 29. The marginal edge of the flange 29 is in turn bent at right angles to extend rearwardly parallel to the wall of the liner, as at 30.

Extending spatially about the liner 27 is an outer casing or shell 32 comprising top wall 33 and side walls 34 formed as a unitary structure rolled from a single sheet of metal, and to which is secured by weld a panel 35 forming the rear wall of the cabinet. The forward marginal edge of the shell is bent at right angles to extend inwardly peripherally about the door opening 29 to form a front wall section 36 spaced forwardly from the front wall portion 29 of the liner 27.

The front wall 36 is of double wall thickness with the metal doubled back upon itself and continuing along the side wall 34 a determinable distance, and then turned at right angles in spaced parallel extension to the doubled wall 36, as at 37.

Extending below and in close proximity to the top wall 33 are parallel angle iron members or rails 39 which extend from the turned flange 37 to the rear panel 35 and is secured at each end by weld or the like. The cross rails 39 are positioned so as to be in planar alignment with a respective side wall 40 of the liner 27. A panel 42 is secured a spatial distance below the bottom wall of the liner by weld to the side walls 34, rear wall 35 and portion 37. The panel 42 serves to partition the casing into an upper and lower compartment. The lower compartment forms the machine compartment 24. Extending between the panel 42 and the cross rails 39 are vertically extending parallel bars or supports 44. The bars 44 are secured by screws at their upper end to the cross rails 39 and at their lower end by screws to lugs 46 welded to the panel 42. The bars 44 are shown arranged in pairs along each of the side walls 40 of the liner, though it will be ap-

plied to the rear wall 35 and portion 37. The bars 44 are secured by screws at their upper end to the cross rails 39 and at their lower end by screws to lugs 46 welded to the panel 42. The bars 44 are shown arranged in pairs along each of the side walls 40 of the liner, though it will be ap-

parent that the number may be varied and, if desired, they may extend along the rear wall of the liner. Each of the bars have a plurality of enlarged openings 47 over which is positioned a U-shaped clip or speed nut 49 adapted to threadably receive the threaded shank 51 of a stud 50 inserted from the compartment side through the wall 40. The stud 50 is provided with a covering 52 and serves as a support for a shelf 53. The studs 50 thus serve to attach the liner to the vertical bar supports and so positioned as to support the shelves within the food storage compartment.

Each of the bars 44 are similarly secured to a respective rail 39 and lug 46 by use of speed nuts clipped to extend over elongated slots 54 formed in each end of the bars 44, and through pass the securing screw threading into the clipped nuts. This arrangement, together with the enlarged openings 47, facilitates for an easy alignment of the bar with respect to openings in the liner through which project the studs 50. The bars may, if desired, be welded to the rails 39 and lugs 46. It will be obvious that this arrangement also permits alignment of the liner relative to the casting for purpose of affixing the breaker strip. By unthreading of the studs the clips become slidable on the bar, and becomes fixed thereto upon fully threading of the stud by drawing the clip together into frictional embracing relation upon the bar.

In the assembling of the cabinet, the vertical supporting bars are first secured in place with the speed nuts clipped in position. The liner is inserted through the front wall opening of the outer shell and between the bars 44 after which the studs are threaded through the wall 40 into the speed nuts. Suitable heat insulation material 55 is inserted between the walls of the liner and the outer casing.

Extending from the front wall section 36 of the casing in a curved arc to interconnect with the rearwardly disposed flange 21 of the liner is a flexible breaker strip 60. The breaker strip is formed of relatively thin metallic sheet having a thickness preferably not exceeding .010 of an inch, and is preferably formed of stainless steel though it may be formed of other material and suitably coated with enamel or it may be plated. The breaker strip is attached by forming a reversely bent U portion 62 along one edge adapted to engage over the forward edge of the double wall 36 and embrace opposite sides thereof. The opposite side of the breaker strip is folded a marginal distance from its edge to engage the front wall 29 with the marginal portion 64 formed to lie snugly against the rearwardly extending flange 30. The end 65 of portion 64 is angularly turned over the edge of the flange 30.

Similar breaker strips extend along the opposite side of the cabinet adjacent the opening 25 and immediately below the food storage compartment and immediately above the food storage compartment. Since the principle of attachment of the other breaker strips is similar to the attachment of breaker strip 60 it was not shown in detail.

Corner strips 70 serve to join the abutting edges of adjacently attached breaker strips. The strips 70 are formed with a face portion 72 adapted to overlie the adjacent ends of the breaker strips. The edges of portion 72 are reversely bent, as at 74, to be again reversely bent, as at 76. The portions 72 and 74 embrace opposite sides of the end of a breaker strip locking thereto the corner strip.

The corner strip is contoured in conformity to the breaker strip and is attached by sliding it downwardly from the outer corner of the abut-

ting breaker strips towards its inner corner with the edge portions 74 engaging behind a respective edge of the breaker strip. A stop is provided by inwardly and downwardly turning the top edge 75 so as to engage over and under the outer side edge of the breaker strip.

By the above described arrangement, the breaker strip is attached without the use of any affixing means, such as screws, nails or the like. 10 By permitting the arrangement of an arcuated breaker strip, it facilitates assembly to the cabinet as well as provides for a more secure attachment in that the ends tend to be flexed into closer abutting relation to the edges of the liner and casing. The corner strips serve to interlock the breaker strips.

The door 26, closing opening 25 to the food storage compartment, comprises an outer sheet metal shell 90 of pan-like contour having upwardly extending sides whose marginal edge is flanged inwardly, as at 92. Extending around the shell is a frame member 94 which is secured by weld to the side wall of the shell. Secured to the frame 94 by metal strips 95 is the door's inner panel 96 which is formed of composition material having low heat conductivity. Suitable heat insulation material 97 is inserted between the inner panel 96 and shell 90. A gasket 99 extends peripherally about the edge of the door and seals against the double wall 36 of the cabinet, preventing air entering the food storage compartment. The gasket is secured by pinching the neck portion between the turned end 92 and metal strip 95 with the enlarged base portion of the gasket extending rearwardly to seal against the frame member.

The circulating air in the food storage compartment is cooled by contact with an evaporator unit 105 located in the compartment, and which is connected to a compressor-condenser unit (not shown) located in the machine compartment and through which circulates refrigerant.

In Fig. 9 the cabinet 110 comprises an outer shell 112, an inner liner 114 and heat insulation 115 therebetween. The outer shell 112 is formed with a front wall section 117 having a flanged edge 119 extending rearwardly parallel to the side wall of the shell. The marginal edge of the inner liner is flanged outwardly, as at 120, and extends about the opening 122 to the food storage compartment 124. The flange 119 terminates a spatial distance from the flange 120 which is set inwardly from the front wall 117 to be joined by a breaker strip 125 extending therebetween in a concave curve, which breaker strip may be constructed of the same material and same thickness as breaker strip 60 shown in Fig. 4. End portion 126 of the breaker strip extends over and rearwardly of the flange 120, being a continuation from the doubled wall marginal edge 122 embracing the face portion of the flange 120. The opposite end of the breaker strip is adapted to frictionally lock over the edge of the flange 119 and is formed with a doubled wall semi-circular portion 127 engaging the corner edge of the front wall 117, thence extending rearwardly with a U-shaped end 130 engaging the edge of the flange 117. By first sliding the end portion 126 over the flange 120, the opposite end 130 is quickly snapped over the end of the flange 119, thus providing an easy and quick means of locking the breaker strip to the cabinet. By arcuating the breaker strip there is eliminated any tendency to flex so as to draw the ends inwardly away from 75 the flanges.

In the form shown in Fig. 10 the outer shell or casing 140 is formed with a front wall portion 142 having a double thickness which is continued a portionable distance along the side wall. The inner liner 144 is formed with a right angle flange 146 extending about opening 148. The marginal edge of the flange 146 extends rearwardly at right angles, as at 150. The front wall 142 of the cabinet is set inwardly of the flange or front wall 146 of the liner and are joined by an arcuate breaker strip 152, preferably of same material and thickness as breaker strips 60 and 125. One end of the breaker strip is formed with a double wall marginal edge 154 having a rearwardly formed U-shaped clip 155 adapted to engage over the edge and embrace the rear side of the front wall 142 with the portion 154 embracing the face section thereof. The opposite side of the breaker strip is locked by a U-shaped clip 156 embracing opposite sides of the flange 150. The clip 156 is an extension from the doubled wall marginal edge 157 which lies in snug engagement against the face of flange 146.

In the form shown in Fig. 11, the outer shell or casing 170 is formed similar to the casing shown in the preferred form having a pocket 172 rearwardly of the double thickness front wall 173, except that the front wall is set inwardly of the front wall portion 174 of the liner 175. The wall 174 is inclined to be in planular alignment with the pocket 173. The wall 174 is flanged to extend rearwardly parallel to sidewall of the liner, as at 180. A breaker strip 176 extends in joining the walls 173 and 174, one end of which is looped, as at 177, and lies within the pocket 172. The opposite end 181 extends over the face of the front wall 174 to be reversely bent and extending rearwardly, thence upwardly along the flange 180 to be turned over its end downwardly, as at 182. The breaker strip 176 may be constructed of the same material and be the same thickness as the other breaker strips disclosed herein.

In the modified form shown in Figs. 12 through 14, there is shown a liner 210 and an outer shell or casing 212, which are joined together by breaker strip 214 immediately adjacent to the door opening 215. The opening is closed by a swingably mounted door 216 and sealed by gasket 219 carried by the door. The liner 210 is supportingly secured in position by hangers 222, which depend from the cross rails 224 secured between the front and rear wall of the casing.

The hanger is secured by screws 225 to a side wall of the liner. Similar hangers 230 extend upwardly from rail 232 secured by weld to the partitioned wall 234 of the cabinet. Screws 225 secure the liner to the hanger 230. Similar hangers (not shown) are provided for supporting the liner at the opposite side wall.

In assembly, the hangers are welded to a respective rail, and the liner is inserted between the hangers and attached by screws, the operator working from within the food storage compartment in threading the screws through the wall of the liner into the hangers.

While I have shown and described the preferred form of my invention, I do not wish to limit myself to the precise details as shown, but wish to avail myself of such variations and modifications as may come within the scope of the appended claims.

I claim:

1. Cabinet construction comprising an outer casing, an inner casing disposed within said outer casing in spaced apart relationship with the front walls of said casings being arranged on substantially the same plane and terminating in spaced apart relationship, horizontally disposed hangers positioned above and below said inner casing, means securing said hangers to said outer casing, vertical members extending parallel to the side walls of said inner casing, means securing said vertical members to said hangers, and means securing said vertical members to said inner casing.

2. Cabinet construction comprising an outer casing, an inner casing disposed within said outer casing in spaced apart relationship with the front walls of said casings being arranged on substantially the same plane and terminating in spaced apart relationship, horizontally disposed hangers positioned above and below said inner casing, means securing said hangers to said outer casing, vertical members extending parallel to the side walls of said inner casing, with each member extending above and below said inner casing, means securing the ends of said vertical members to said hangers, means securing said vertical members between the ends thereof to the side walls of said inner casing and a breaker strip extending between the outer and inner casings at the front of the cabinet.

MARTIN J. GOULOZE.
